LAVATORY

William H. Armstrong, Bloomfield Hills, Mich., assignor
to Borg-Warner Corporation, a corporation of Illinois

Filed Jan. 21, 1965, Ser. No. 83,522

Term of patent 14 years

(Cl. D4—2)

FIG. 1 is a perspective view taken along one side of a lavatory showing my new design;
FIG. 2 is a top plan view thereof;
FIG. 3 is a front elevation view thereof; and
FIG. 4 is an elevation view taken from the sides shown in FIG. 1 (the opposite side being a mirror image of the side shown).

The dominant features of my design reside in the portions shown in full lines.

This application is a continuation-in-part of design patent application Serial No. 72,057, filed October 10, 1962, and now abandoned.

I claim:

The ornamental design for a lavatory, substantially as shown and described.
